UNITED STATES PATENT OFFICE.

JACKSON L. WAITE, OF MIDDLETOWN, OHIO, ASSIGNOR, BY DIRECT AND MESNE ASSIGNMENTS, OF ONE-FOURTH TO ALBERT S. FENZEL, NINE-FORTIETHS TO CASPAR FENZEL, AND ONE-TWENTIETH TO JOSEPH M. JENETSKY, ALL OF MIDDLETOWN, OHIO.

OSCILLATING MACHINE.

Application filed January 17, 1921. Serial No. 437,646.

To all whom it may concern:

Be it known that I, JACKSON L. WAITE, a citizen of the United States, residing at Middletown, in the county of Butler and State of Ohio, have invented certain new and useful Improvements in Oscillating Machines, of which the following is a specification, reference being had therein to the accompanying drawing.

10 My invention relates to oscillating mechanism.

In the particular adaptation that I have shown this oscillating mechanism is applied to an electric heater and is used for moving the heating reflector from position to position.

It is the object of my invention to provide an oscillating mechanism which is electrically operated and which will move the heating reflector or similar mechanism at the will of the operator. It is my object to provide a mechanism for continuously operating the oscillating mechanism or for bringing it to a position of rest and at the same time maintaining the rest of the mechanism in operation, as for instance, the heater.

It is my object to provide an oscillating mechanism, the movement of which may be adjusted. It is my object to provide a mechanism which will prevent a jar at the end of each movement and consequent injury to the mechanism. It is an object of my invention to provide a mechanism, the speed of oscillating of which may be adjusted. It is my object to provide a mechanism which may utilize either direct or alternating current without any modification of the mechanism.

40 Referring to the drawings:

Fig. 1, is a perspective of an electric heater equipped with my mechanism;

Fig. 2, is a plan view of the bottom of the heater inverted in order to show the mechanism therein;

Fig. 3, is a section of this inverted bottom on the line *a—a* of Figure 2;

Fig. 4, is a section on the line *b—b* of Figure 2;

50 Fig. 5, is a section of the solenoid employed.

Referring to the drawings, 1 is a base or housing of any suitable configuration, 2 is a supporting standard mounted there-

on containing the shaft 3, which is oscillated. This shaft supports and oscillates any desired mechanism, as for instance a heater 4. It is understood that I do not desire to confine my invention to this adaptation, but merely illustrate this as one of the forms for the use of my invention.

Referring more particularly to Figure 2, where the mechanism will be seen in a view which is looking down upon the inverted bottom, comprising the casing 1, which is the wall upon which is mounted a support 5 fastened to the casing by the screws 6—6. This support 5 is in the shape of a bracket which has located centrally at the end thereof a screw plug 7 upon which is mounted the shaft 3 and which is used to adjust the vertical position of the shaft 3. Upon the shaft 3 (see Figures 3 and 4) is mounted a drum 8. This drum is fixed to the shaft and carries a pair of fingers 9 and 10 laterally extending therefrom at right angles to the shaft 3. These are the contact fingers, the function of which will be described later. We thus have a shaft which can be oscillated with a drum mounted thereon, the position of the whole being subject to adjustment vertically.

Referring to Figure 4, there will be seen that there is an insulated covering 11 on the member 9. The contact finger or blade 10 has no covering to insulate it.

A connecting bridge 12 slides back and forth at an angle to the shaft 3 which is inserted in the slot 13 of the member 12. This member 12 carries on the right hand side (see Figure 2) a shoe 14 sliding in guideways 15—15 attached by the screws 16 to the casing 1. This shoe has mounted upon it a bifurcated member 17 against the sides of which the finger 17' oscillates and which acts as a limiting member or buffer member for limiting the swing of the shaft 3 and the mechanism carried by it.

At the left hand end of the member 12 is another shoe 18 traveling in guideways 19—19. This shoe has an upwardly projecting portion 20 internally threaded (see Figure 3) at 21. This internal thread receives the external thread on an adjusting member 22 which is carried in the frame 1 and is actuated by a knurled head 23. A positioning nut 24 embraces the portion of the frame or casing 1 between it and 23 while 22 freely

rotates in 1. By rotating this knurled member the position of the shoes 18 and 14 are adjusted and simultaneously the buffer member 17 and contact member 25. The contact head 26, which is carried by the contact member 25 and in turn by the shoe 18, is adapted to be moved into its several positions by the knurled member mentioned above. It will be readily understood that it is not essential to my invention that the contact member and the buffer member be actuated together; they may be actuated separately if desired, but I have found that it is convenient to mount them on the same actuating member for simultaneous adjustment in which there is some advantage under certain conditions.

It will be observed that as the contact members 9 and 10 swing back and forth that a contact will be made between 26 and 10 in one direction and the contact broken by 11 in the other direction as 26 passes between 11 and 10 and upon 10 while going in one direction and on the outside of 11 away from 10 when going in the other direction, when the contact is broken as 26 is riding upon the insulating material of 11.

The swinging back and forth of the shaft 3 and the speed of that movement may be controlled, if desired, by a brake consisting of a brake-shoe, preferably a felt pad 27, mounted on a brake member 28, which is mounted upon a shoe 29 traveling in a guide way 30. 31 is a knurled head that actuates a threaded member 32 which travels in 29 for molding it inwardly and outwardly. When the brake-shoe 27 is brought in contact with the shaft 3 it will retard the movement of that shaft.

40 The shaft 3 is oscillated by the following mechanism. Upon the drum 8 is partially wound a band or cable 33 attached at one end to the drum and connected to a core 34 of a solenoid 35. The coil 36 within the soft iron casing 37 of this solenoid generally designated 35 is connected at its respective ends to the posts 38 and 39 upon the end piece or cap member 40. The member 37 is projected inwardly at 41. It has knotted upon it, between 40 and its closed end, a copper ring 42 which is not insulated from the soft iron of 41. 34 is of soft iron and extends within the coil to a point where it is closely adjacent at 43 to the end of 41. Recessed in the end of 34, adjacent to 41, is a copper ring 44.

60 The purpose of this arrangement is to provide a means, such as the copper rings, to prevent the current going to zero when alternating current is used and thus placing difficulties in the way of operating this solenoid on alternating current. By having this arrangement either alternating or direct current may be used satisfactorily and successfully. On the other side of the drum

8 is a spring 45 connected to a cable 46 which is wound about the drum partially and attached at one end thereto. This spring is connected to a shoe 47 traveling in guideways 48 which is actuated by a threaded member 49. This threaded member, like the similar mechanisms in this construction, is actuated by a knurled head 50. Thus the tension of the spring may be suitably adjusted.

75

Current is conveyed from the main current lead 51 to 52 and thence to the coil of the solenoid as at 53. The other end of the coil is connected at 54 to the wire 55, which is connected to the binding post 56 80 and to the stationary contact member 57 which communicates by the contact head 58 with 10 with which, or a portion of which, it is in sliding engagement. (See Figure 4.)

On the other side from 51 the wire 58 and 85 the wire 59 leads to the base of the switch member at 60. This switch member 61 is adapted to make contact with 62 and 63. When it is in contact with 63 the current can then flow over 64 until it is conveyed to the 90 contact member 25 thence to the contact head 26 which intermittently engages with 10, thus completing the circuit.

It will be observed that this switch 61 has a weight 65 thereon. This weight is placed 95 on the switch arm 61 at any position. It is preferably placed in an outer position, but in the drawing it has been moved inwardly so as to disclose the other mechanism adjacent thereto. If by accident the heater is 100 turned over so that the face of it would be upon the floor, the weighted arm of the switch would fall by gravity to its off-position thus automatically cutting off the 105 heater entirely.

The switch arm is shown in its neutral position where the entire mechanism is dead. When it is placed in position to make contact with 62 then the heater is turned on through the wire 66, 67, 68.

110

When the arm is moved to 63 the heater is both turned on and the solenoid 35 is energized. The solenoid 35 may be retained by any means, as for instance the strap 69.

115

Method of operation.

The operator may turn the switch until it rests on 63. The coil being energized it will attract to it 34 and thus move the shaft 3 in one direction so long as the contact is made between 26 and 10. The action of the coil will draw 34 to a point where the contact between 26 and 10 will be broken. Then the spring will withdraw the mechanism in its opposite direction rotating the shaft 3 125 and the drum 8, the spring having been expanded by the action of 34. During this period the contact member 26 is riding upon the insulated surface 11. As soon as it gets to the edge of 11, which has lifted it out 130

of its normal plane, it will drop back upon 10. It is understood that 25 is in the nature of a plate spring which would normally keep the head 26 in engagement with 10 until the contact is broken and the knife edge 5 of 9 picks up 26 while 11 moves under it in the direction of the arrow being drawn in that direction by the pull of the spring 45.

If it is desired to reduce the speed of reciprocation back and forth then the brake-shoe 10 27 can be brought in engagement with the shaft 3.

If it is desired to adjust the time of contact or the extent of swing then the knurled member 23 can be actuated.

If it is desired to adjust the tension of the spring then the knurled member 50 can be actuated.

While I have shown and described certain 20 features as constituting my invention, it will be understood that parts have been shown for purposes of illustration only, and that I do not desire to be limited to such details, as obvious modifications will occur to a person skilled in the art.

Having thus fully described my invention, what I claim as new and desire to secure by Letters Patent, is:—

1. In combination, a member to be oscillated, tension means including a cord extending around said member to move said member in one direction, electrically operated means including flexible means wound about said member to move said member in the other direction, means for intermittently energizing said electrically operated means, and means for adjusting the time of energizing said electrically operated means.

2. In combination, a member to be oscillated, tension means including a cord wrapped about said member to move said member in one direction, electrically operated means to move said member in the other direction, means for intermittently energizing said electrically operated means, means for adjusting the time of energizing said electrically operated means, means for absorbing the shock at either end of the oscillating movement of said member, and means for adjusting the speed of movement of said oscillating member.

3. In combination, an oscillatable drum, mechanical tension means including flexible means around said drum for moving said drum in one direction, electrically operated means including flexible means around the drum for intermittently moving said drum in the other direction, means for adjusting the tension of the mechanical means, and means for adjusting the time of energizing the electrically operated means, whereby said member may be oscillated fast or slow as desired.

4. In combination, a member to be oscillated, tension means wrapped about said

member for moving it in one direction, intermittently operated electrical means for moving it in the other direction, means for adjusting the tension of the first mentioned moving means, means for adjusting the time 70 of energizing of the second mentioned moving means, means for damping the speed of oscillation, and means to absorb the shock of reversal of movement at either end of the stroke.

5. In combination, a member to be oscillated, tension means wrapped about said member for moving it in one direction, intermittently operated electrical means for moving it in the other direction, means for 80 adjusting the tension of the first mentioned moving means, means for adjusting the time of energizing of the second mentioned moving means, means for damping the speed of reciprocation, means to absorb the shock of reversal of movement at either end of the stroke, and means for permitting the use of either alternating or direct current as an actuating means.

6. In combination, a supporting casing, an oscillating member journaled therein and supported thereby, a drum on one end of said oscillating member, a resilient means, a cable having one end wrapped about said drum and the other end attached to said resilient means, said resilient means being adjustably attached to said supporting frame; a solenoid, a second cable having one end wrapped about said drum and the other end attached to a member of the solenoid, a contact carried by said drum for intermittently energizing said solenoid, whereby said member may be oscillated in either direction.

7. In combination, a supporting frame, an oscillating member journaled therein and supported thereby, a drum on one end of said oscillating member, a resilient means, a cable having one end wrapped about said drum and the other end attached to said resilient means, said resilient means being adjustably attached to said supporting frame; a solenoid, a second cable having one end attached to said drum and the other end attached to a movable member of the solenoid, a contact member adjustably secured in said frame consisting of a plate spring and a contact head, a knife contact carried by said drum adapted to make contact with said head to energize the solenoid, an insulated 120 knife member adjacent said contact knife member for lifting said contact head away from said contact knife, whereby said member may be oscillated in either direction.

8. In combination, a supporting casing, an oscillating member journaled therein and supported thereby, a drum on one end of said oscillating member, a resilient means, a cable having one end attached to said drum and the other end attached to said re-

silent means, said resilient means being adjustably attached to said supporting frame; a solenoid, a second cable having one end wrapped about said drum and the other end attached to the movable member of the solenoid; a contact member adjustably secured in said frame consisting of a plate spring and contact head, a knife contact carried by said drum adapted to make contact with said head to energize the solenoid, an insulated knife member adjacent said contact knife member for lifting said contact head away from said contact knife, a finger carried by said drum and a bifurcated member between the arms of which said finger travels and adapted to make contact with said

finger at either end of its reciprocatory movement to absorb the shock at the end of its movement, whereby said member may be reciprocated in either direction. 20

9. A tiltable motor comprising, a part to be oscillated, means to move said part in one direction, electrical means adapted to move said part in the other direction, means for adjusting the intermittent action of the electrical means, a switch connected with said electrical means, and means on said switch for moving it to neutral position when said motor is tilted in a certain direction. 25

In testimony whereof, I affix my signature. 30

JACKSON L. WAITE.
